UNITED STATES PATENT OFFICE.

HERBERT L. NELSON, OF DETROIT, MICHIGAN.

SUPPORT FOR FIRE-EXTINGUISHER CONTAINERS.

1,088,444.

Specification of Letters Patent. Patented Feb. 24, 1914.

Application filed March 8, 1913. Serial No. 752,946.

To all whom it may concern:

Be it known that I, HERBERT L. NELSON, citizen of the United States, residing at Detroit, in the county of Wayne, State of Michigan, have invented certain new and useful Improvements in Supports for Fire-Extinguisher Containers, and do declare the following to be a full, clear, and exact description of the invention, such as will enable others skilled in the art to which it appertains to make and use the same, reference being had to the accompanying drawings, and to the characters of reference marked thereon, which form a part of this specification.

This invention relates to a support for a fire extinguisher container, and consists in the construction and arrangement of parts hereinafter more fully set forth and claimed.

The object of the invention is to provide simple and efficient means for mounting a container adapted to contain a chemical fire extinguisher, preferably in the form of powder, in such manner as to enable said container to be quickly removed from said support, provision being made for causing the container to open by the operation of removing it from its mountings so as to render the contents ready for use without further procedure.

The invention contemplates such an arrangement of parts as will firmly retain the container in place, enable a ready removal thereof for use, and permit the container to be easily returned to its mountings.

The above object is attained by the structure illustrated in the accompanying drawings, in which:

Figure 1 is an elevation showing one embodiment of my invention. Fig. 2 is a perspective view showing a fragmentary portion of the foot board of an automobile, illustrating the manner of mounting my container thereon to serve as a foot rail, a portion of the end plate of one of the supports being broken away. Fig. 3 is an enlarged longitudinal section through one of the supporting members and one end of the container. Fig. 4 is a transverse section as on line 4—4 of Fig. 1. Fig. 5 is a perspective view of the cap or cover which closes the end of the container.

Referring to the drawings by the characters of reference marked thereon, 1 designates a tubular container which may be of any desired length and of any cross-sectional

area to afford the requisite capacity. One end of the container as at 2 is provided with an opening through which it may be filled. Closing said opening to retain the contents within the container is a cover 3 which fits tightly to normally maintain itself in place. Projecting centrally from the cover 3 is a rigid stem 4 having at its outer end a thread 5.

The container is supported by bracket members 6 and 7, respectively, said brackets being provided with extending feet 8 to enable them to be secured in place. The bracket 6 is provided with a laterally projecting saddle member 9 adapted to receive the end of the container, and with a vertical end plate 10. Through said end plate 10 is formed an aperture 11 adapted to receive the stem 4 of the cover of the container which passes freely therethrough as shown in Fig. 3. The bracket 7 is also provided with a laterally extending saddle member 12 and with an end plate 13. Secured within the saddle 12 by the bolts 14, or in any other suitable manner, are the curved spring jaws 15, whose terminals are bent outwardly as shown at 16 to allow of the ready entrance of the tubular container therebetween, said jaws being sufficiently resilient to allow the container to be passed thereinto, when they will spring around the container and hold it in place.

To place the tubular container in the supporting brackets, the stem 4 of the cover 3 is passed through the opening 11 in the end plate of bracket 6, and the opposite end of the container forced downwardly into the saddle 12 of bracket 7 between the spring jaws 15. The nut 17 is then screwed onto the threaded end of the stem 4, as clearly shown in Fig. 3, when the container will be securely and firmly supported in place, enabling it to be employed as a foot rail in an automobile as shown in Fig. 2, at the back of the front seats to serve as a robe rail, or upon the dash, as may be desired. The brackets 6 and 7 firmly support the container wherever placed in such a position that when desired for use it may be grasped by the hand at the end opposite that closed by the cover and drawn outwardly from between the spring jaws 15. This operation swings the container to an angular position with respect to the end plate 10 of the bracket 6, as shown by dotted lines in Fig. 3, causing the cover which is attached to the plate 10 by the stem 4 and nut 17 to with-

- draw from the opening in the end thereof, rendering the container ready for use and enabling its contents to be dashed upon a fire without the further procedure of removing 5 the cover. The container may be replaced in its supporting brackets by unscrewing the nut 17, removing the cover from the plate 10 and replacing it in the opening in the end of the container, when said container may be 10 placed in position in its mountings by again passing the stem 4 through the opening 11 in the end plate 10 and forcing the opposite end between the jaws 15 of the bracket 7. The nut 17 may then be screwed into place 15 upon the threaded stem of the cover, and the parts will be in position for further use.
- Having thus fully set forth my invention, what I claim as new, and desire to secure by Letters Patent, is:—
- 20 1. A support for a fire extinguisher container comprising bracket members, one of said members having an end plate provided with an aperture, a cover for the container having a stem adapted to pass through said 25 aperture, a nut on the end of said stem, and

spring members carried by the other bracket member adapted to engage and frictionally retain in place the end of the container opposite to that having the cover.

2. A support for a fire extinguisher container comprising opposed brackets, each of which is provided with a saddle member, a tubular container adapted to extend between said brackets and lie in said saddle members, a cover closing one end of said container, a stem projecting from the cover and passing through the end plate of the bracket member, means for preventing the withdrawal of said stem from said plate, and spring jaws extending from the saddle of the other bracket member adapted to frictionally embrace the end of the container to retain it detachably in position.

In testimony whereof, I sign this specification in the presence of two witnesses.

HERBERT L. NELSON.
